UNITED STATES PATENT OFFICE.

PETER T. GRIFFIN, OF VAN ZANDT, WASHINGTON.

REGISTER FOR POOL TABLES.

Application filed May 12, 1921. Serial No. 468,008.

To all whom it may concern:

Be it known that I, PETER T. GRIFFIN, a citizen of the United States, residing at Van Zandt, in the county of Whatcom and State of Washington, have invented a new and useful Register for Pool Tables, of which the following is a specification.

This invention relates to pool or billiard table attachments, the primary object of the invention being to provide an attachment to be moved to a position over the surface of the table in the path of travel of the usual rack when the same is being employed to rack the balls.

15 A further object of the invention is to provide a device of this character which will register each rack of the pool balls, thereby indicating the number of games which have been played on the table.

20 A still further object of the invention is to provide means for locking the device against movement unless the movable elements of the attachment are in positions to cause the registering or recording mechanism to operate.

With the foregoing and other objects in view which will appear as the description proceeds, the invention resides in the combination and arrangement of parts and in the 30 details of construction hereinafter described and claimed, it being understood that changes in the precise embodiment of the invention herein disclosed, may be made within the scope of what is claimed, without departing from the spirit of the invention.

Referring to the drawings:—

Figure 1 illustrates a fragmental plan view of a pool table showing the invention 40 as applied thereto.

Figure 2 illustrates a fragmental sectional view showing the attachment in side elevation.

Figure 3 illustrates a detail view of the 45 locking means forming a part of the invention.

Figure 4 is a longitudinal sectional view through the attachment.

Referring to the drawings in detail, the 50 table to which the invention is applied is indicated by the reference character 5 and provides the support for the attachment.

The device comprises a hinge section 6 which is secured to the edges of the table, 55 which hinge has connection with the arm 7,

which, when the device is in operation lies directly over the rail of the table, the forward end of the arm extending to a position beyond the rail, where the same has connection with the tubular body portion 8 of the 60 device.

Operating within the tubular body portion 8 is a tubular member 9 which has an opening 10 adapted to register with the opening 11 formed in the body portion 8, so 65 that when the openings 10 and 11 are in registry with each other, numerals on the tape 12 may be readily observed therethrough.

Connecting the side walls of the member 70 9, are the shafts 13 and 14, the shaft 13 providing a support for the sprocket wheel 15 which moves thereon, while the shaft 14 forms a support for the sprocket wheel 16 which is secured to the shaft. Mounted on 75 the shaft is a ratchet wheel 17 which moves the shaft 14, to cause the rotation of the sprocket wheel 16, which imparts rotary movement to the sprocket wheel 15 through the medium of the tape 12, that is provided 80 with a plurality of links 18 cooperating with the teeth of the sprocket wheels.

A shaft 19 is also supported within the tubular member 9, the shaft being provided with an opening to accommodate the rod 20, 85 which rod has an offset portion 21 provided with a finger 22 which cooperates with the ratchet wheel 17 for moving the same. This rod also extends through an eye bolt 23 carried by the body portion 8, there being a retractable spring 24 mounted on the rod, which coiled spring normally holds the rod in a position as indicated by Figure 4, one end of the spring 24 being connected with the head 25, while the opposite end of the 90 spring has connection with the member 23. A head 25 is formed at one end of the rod and provides a seat for the retractable spring 24, so that movement of the tubular member 9 within the body portion 8, will 95 cause the spring 24 to contract.

The body portion 8 is provided with a lateral opening which is adapted to register with a suitable opening provided in the tubular member 9, which openings when in 105 registry with each other, accommodate the locking pin 26, which is held within the openings by means of the coiled spring 27 which bears against the bracket 28, the pin 26 being however provided with a head 29, 110

affording means to permit the operator to remove the pin 26 from the registering openings to unlock the tubular member 9.

Positioned within the body portion 8 is a receptacle 30 adapted to receive the coins which are passed into the body portion through the slot 31.

In the operation of the device, the member 9 is of a length so that the outer extremity thereof will extend beyond a position on the table where the balls are racked, so that to accomplish the racking of the balls, it will be necessary to move the rack 32 rearwardly moving also the tubular member 9 so that when the rack is in a position for racking the balls, the tubular member 9 is moved within the body portion 8 carrying with it the gears or sprocket wheels 15 and 16.

As the tubular member 9 moves within the body portion 8, the ratchet wheel 17 contacts with the finger 22 to cause the tape 12 to be moved one point, to bring a number under the openings 10 and 11 where it may be observed.

It might be further stated however that prior to the racking of the balls, it is necessary to remove the pin 26 from its opening in the tubular member 9, thereby permitting the tubular member to move within the body portion, it being understood that the pin

locks the apparatus against movement to prevent the device from being used independently of the registering mechanism.

Having thus described the invention, what is claimed as new is:—

In a registering device for pool tables comprising a support, a hollow body portion having a slot formed therein, a receptacle within the body portion and having a slot registering with the first mentioned slot, a tubular member positioned in one end of the body portion and carrying sprocket wheels, said body portion and tubular member having registering openings, indicating means operated by the sprocket wheels, and adapted to be viewed through the registering openings, a ratchet wheel associated with one of the sprockets, an operating rod carrying a finger adapted to cooperate with the ratchet wheel to rotate the same, upon movement of the tubular member within the body portion, and means for returning the tubular member to its inactive position.

In testimony that I claim the foregoing as my own, I have hereto affixed my signature in the presence of two witnesses.

PETER T. GRIFFIN.
